UNITED STATES PATENT OFFICE.

JULES COURTIER, OF PARIS, FRANCE.

RESTORER OF NORMAL IGNITION FOR DUAL IGNITION APPARATUS OF INTERNAL-COMBUSTION ENGINES.

Application filed July 31, 1923. Serial No. 654,879.

To all whom it may concern:

Be it known that I, JULES COURTIER, a citizen of the Republic of France, of 20 Rue Ernest Cresson, Paris, France, have invented Improvements in or Relating to Restorers of Normal Ignition for Dual Ignition Apparatus of Internal-Combustion Engines, of which the following is a full, clear, and exact description.

10 This invention relates to an auxiliary apparatus for internal combustion engines having dual ignition for producing regulable break sparks for doing away with misfires due to the sooting of sparking plugs and automatically cleaning these plugs during the running of the engines and of the vehicles driven by them.

15 This apparatus permits a single controlling organ to effect the introduction of break sparks regulable at will, separately into one or the other of two ignition circuits.

20 The general arrangement is such that when the apparatus is at rest the two ignitions work without any secondary spark gap, and when one of the ignitions is working with break sparks the other ignition continues to work without break sparks.

25 The invention is represented in the drawing, by way of example only, wherein there is shown an arrangement of the apparatus comprising two pairs of contacts capable of being separated to any desired extent, each pair corresponding with one ignition.

30 As shown in the drawing each of the pairs of contact rods A¹ and A² (corresponding to the ignition circuits M¹ and M²) is composed of a fixed contact and of a movable contact. The fixed contacts 1 and 1', are mounted in a block of insulating material 2, and they 35 project from the block into the interior of cavities 3, 3', and are respectively connected to one of the poles of the electric current by plate springs 4, 4'; fixed to the terminals 5, 5' which are mounted in an insulating casing 6. These fixed contacts 1 and 1' are provided with projecting flanges 7, 7'.

40 The movable contacts 8, 8', also provided with projecting flanges 7, 7', are themselves mounted so as to project to the interior of the cavities 3, 3', below the fixed contacts 1, 1', and to slide in sockets 9, 9', mounted in the insulating block 2.

45 They each comprise a tubular part 10, 10'. These tubular parts, provided with lateral 50 openings 11, 11', are respectively closed at

their lower part by screw plugs 12, 12'. In the interior of the tubes 10, 10' are placed coiled springs 13, 13', resting upon the pistons 14, 14'. The movable contacts 8, 8' are connected to the second pole of the current by plate springs 15, 15', fixed to the terminals 17, 17', mounted in the casing 6. The screw plugs 12, 12' rest freely upon the ends 16, 16' of these springs.

55 A rocking piece 18, made of insulating material turning upon a pivot 19, is provided with arms 20, 20', whose ends are constituted by heads 21, 21', projecting respectively into the interior of the tubes 10, 10', through openings 11, 11', between the screw plugs 12, 12', and the pistons 14 and 14'.

60 The rocking piece 18 is formed at its upper part with a slot 22 in which is freely located the finger 23 of a disc 24 turning upon its centre 25 under the action of the handle 26.

65 Notches 27 are provided upon the casing 6. The object of these notches will be hereinafter explained.

70 The working of this apparatus is as follows:

75 When the handle 26 is moved in the direction of the arrow *a*, the finger 23 causes the rocking piece 18 to pivot towards the left of the figure. The arm 20 of the rocking piece presses, through its head 21, upon the screw plug 12, which bearing freely upon the end 16 of the plate spring 15 causes the latter to bend downwards. From this it follows that the movable contact 8 is lowered and, sliding within the socket 9, it moves away from the fixed contact 1.

80 In the open space between the fixed contact 1 and the movable contact 8 there is produced a break spark whose length increases as the handle 26 continues its movement in the direction of the arrow *a*.

85 The handle 26 is provided upon its lower face with a stud 28, which enables it to be secured in one of the notches 27 of the casing 6. In this manner it is possible to regulate the gap between the fixed contact 1 and movable contact 8, and consequently the length of the spark between these contacts.

90 At the same time as the arm 20 is being lowered, the arm 20' is moved upwards; the head 21' presses upon the piston 14' and compresses the coiled spring 13'. An upward pressure is thereby produced upon the inner end 29 of the tube 10', so the con-

100

105

110

110

tact between the movable contact 8' and the fixed contact 1' is so much the better ensured.

It will be understood that in operating 5 the handle 26 in the direction of the arrow *b*, the movable contact 8' will be removed from the fixed contact 1', while ensuring on the other hand the thorough pressure of the movable contact 8 against the fixed contact 10 1.

When in the normal position of rest, the arms 20 and 20' of the rocking piece 18 remain horizontal as shown in the figure, and the plate springs 15 and 15', through 15 their ends 16, and 16', ensure contacts between the contacts 1 and 8 on the one hand and the contacts 1' and 8' on the other hand. The two circuits M¹ and M² then work without any secondary spark gap.

20 The cavities 3, 3' are enclosed by sheets of mica or any other suitable insulating material.

The apparatus above described is used in the following manner:

25 In engines with fixed cylinders, the apparatus described is inserted so that it is arranged, as far as concerns the electrical connections, between the collector and the distributor of the magneto of the first ignition circuit through its terminals 5 and 17, and between the collector and the distributor of the magneto of the second ignition circuit through its terminals 5' and 17'. As concerns the electrical connections to rotary 30 engines, the apparatus is inserted between the collector of the magneto and the distributor of the cylinders of the first and of the second ignition circuits respectively through the same terminals, 5, 17 and 5', 17'. 35

40 In case of misfires, the handle 26 is moved in the direction of one of the arrows *a* or *b* proceeding gradually notch by notch. If, in the first direction chosen the misfires are heard to cease, the handle is secured at the 45 point where it was noticed that good ignition was reestablished. If the handle is moved in one direction until the last notch is reached without ignition being reestablished, it is concluded that the misfire is 50 produced in the other ignition circuit. The handle is then brought back to its medium position of zero and it is advanced gradually notch by notch in the opposite direction.

55 After a few trials the motor is heard to be working normally without any misfire. The handle is secured at the point where the ignition was re-established. At the end of a few minutes, necessary for the cleaning of the sparking plug, the handle is returned to 60 zero.

I claim:

1. Internal combustion auxiliary apparatus with double ignition circuit intended to produce regulable disruptive sparks, to 65 eliminate misfires and fouling spark plugs

during travel, comprising two pairs of conductive members, one interposed in the first, the other in the second high tension circuit, a control member adapted to act on said conductor members, means by which said control members act on said conductor members to simultaneously close the two circuits or to open one of the circuits, thus producing disruptive sparks in the circuit. 70

2. Internal combustion auxiliary apparatus with double ignition circuit intended to produce regulable disruptive sparks to eliminate misfires and fouling spark plugs during travel, comprising two pairs of conducting members inserted one in the first 80 and the other in the second high tension ignition circuit, a control member adapted to operate the said conducting members, means by which the said control member operates the said conducting members for closing simultaneously the two ignition circuits, or for opening in a regulable manner one of the two circuits, thus producing disruptive sparks in the circuit. 85

3. Internal combustion auxiliary apparatus with double ignition circuit intended to produce regulable disruptive sparks to eliminate misfires and fouling spark plugs during travel, comprising two pairs of conducting members inserted one in the first 90 and the other in the second high tension ignition circuit, a control member adapted to operate the said conducting members, a medium position mark for this control member and two series of divisions in one and the other direction apart from this medium position mark, means by which the said control member operates the said conducting member for closing simultaneously the 95 two ignition circuits or for opening in a regulable manner one of the two ignition circuits thus producing disruptive sparks in the circuit. 100

4. An auxiliary apparatus for internal combustion engines having dual ignition, comprising one pair of contacts inserted in each of the two high tension ignition circuits, the two pairs of contacts consisting each of a fixed contact and a movable contact, an insulating rocking piece operating the two movable contacts and moving gradually each movable contact away from its corresponding contact, means for controlling the slope of the rocking piece. 110 115

5. Internal combustion auxiliary apparatus with double ignition circuit intended to produce regulable disruptive sparks to eliminate misfires and fouling spark plugs during travel, comprising two pairs of contacts one interposed in the first and the other in the second high tension circuit and consisting each of a fixed contact and a movable contact, an insulating rocking piece separating gradually each movable contact 120 125 from its corresponding fixed contact, means 130

by which the insulating rocking piece acts elastically on the movable contacts, means for regulating the slope of the said rocking piece.

5 6. Internal combustion auxiliary apparatus with double ignition circuit intended to produce regulable disruptive sparks to eliminate misfires and fouling spark plugs during travel, comprising two pairs of contacts one interposed in the first and the other in the second high tension circuit and each consisting of a fixed contact and a movable contact, springs operating the movable contacts, an insulating rocking piece operating 10 the springs, a handle to operate the rocking piece.

15 7. Internal combustion auxiliary apparatus with double ignition circuit intended to produce regulable disruptive sparks to 20 eliminate misfires and fouling spark plugs during travel, comprising two pairs of contacts one interposed in the first and the other in the second high tension circuit and each consisting of a fixed contact and a mov-

able contact, springs operating the movable contacts, an insulating rocking piece operating the springs, a handle to operate the rocking piece, a medium position mark for this handle, notches in one and the other side from the medium position mark.

30

8. An auxiliary apparatus for internal combustion engines having dual ignition comprising two pairs of conducting members inserted one in the first and the other in the second high tension circuit, a control member to operate the said conducting member, means by which the said control member operates the said conducting members for closing simultaneously the two high tension ignition circuits or for inserting in 35 one of the two circuits spark gaps in series in a regulable manner.

40 The foregoing specification of my improvements in or relating to dual ignition apparatus for internal combustion engines, 45 signed by me this 18th day of July 1923.

JULES COURTIER.
